UNITED STATES PATENT OFFICE

LEROY C. DOANE, OF MERIDEN, CONNECTICUT, ASSIGNOR TO THE MILLER COMPANY, OF MERIDEN, CONNECTICUT, A CORPORATION OF CONNECTICUT

DUSTPROOF LIGHTING UNIT

Application filed April 13, 1928. Serial No. 269,653.

The present invention relates to dustproof lighting units and is more particularly directed toward a lighting unit suitable for use where it is exposed and subject to wind, 5 weather and vibration.

The present invention contemplates an enclosed lighting unit suitable for the above purposes wherein a single inclosing glass globe is mounted about the light source in 10 such a manner that the entrance of dust or rain is effectively prevented while at the same time the inclosing globe may be readily released for inspection, cleaning or replacement. The invention also contemplates a 15 suitable form of globe support which is capable of being made out of heavy rugged parts which will withstand vibration and at the same time provide a weather proof inclosure for the electrical parts of the unit.

20 Another object of the invention is to provide a unit of this nature in which it is unnecessary to use any tools when removing or replacing a globe.

The accompanying drawings show, for 25 purposes of illustrating the present invention, one of the many possible embodiments in which the invention may take form, it being understood that the drawings are illustrative of the invention rather than limiting 30 the same.

In these drawings:

Figure 1 is a vertical sectional view through the lighting unit with parts in elevation; and

35 Figure 2 is a horizontal section view on the line 2—2 of Figure 1.

In the present form of construction the upper part of the lighting unit is made in the form of a canopy 10 having a downwardly 40 and inwardly converging portion indicated at 11, and provided with a plurality of inwardly extending lugs 12 drilled to receive screws 13. This canopy 10 may be conveniently made in the form of a heavy rugged 45 aluminum casting and is detachably fastened to a ring-like member 14.

This ring-like member 14 functions, in the present form of construction, as both a socket support and a globe support. As here shown 50 it is provided with an inwardly directed

flange 15 in which is mounted a lamp socket indicated at 16. The screws 13 are threaded into suitable tapped holes in this flange so as to fasten the members 10 and 14 together. The unit may be supported by means of supporting rods 17 fastened to a cross bar 18 and provided at their lower ends with nuts 19. The lower portion of the ring-like member 14 is provided, as here shown, with three downwardly and outwardly extending lugs 20. Each of these lugs has a horizontal portion 21, a vertical portion 22 and a lower horizontal foot portion 23. The upper face of the horizontal portion 21 is notched as indicated at 24 to receive a comparatively rigid sheet metal finger 25. This finger extends inwardly as indicated in the drawing and passes through a slot 25' in the lug. The inner upper end of the finger 25 is provided with a hooked end 26 which is passed up into the slot in the lug, the finger 25 also extending outwardly and downwardly as indicated. The free end 27 of the finger extends beyond the foot 23. The finger is supported and held in place on the lug by means of a coiled 75 spring 28 wound around a pin 29 which is fastened to the finger and which passes through a hole in the foot 23 as indicated.

The outer surface of the ring-like member 14 is as here shown slightly larger in diameter than the lower portion of the canopy. This outer surface of the ring 14 is threaded as indicated at 30 and a cover ring 31 is threaded onto the ring 14. This cover ring may be moved up and down by turning it 80 along the threads. The ring extends outwardly and downwardly as shown and the skirt 32 of the ring is provided with a gasket member 33. This gasket may be made up in the form of a strip of woven asbestos tubing 34 which is drawn over a split spring ring 34'. The split ring will hold the gasket in place in the skirt of the cover ring 31 and provide a very effective dustproof joint when the globe is inserted in place. 85

To insert the globe in place the ring 31 is revolved backwardly to raise it up to the dot and dash line position. A conventional globe such as indicated at 35 has a lip or rim as indicated at 36 and an upper covering wall 100

37. The opening in the upper part of the globe is the proper size to permit passing it up over two of the lugs and fingers and turning it about so that the shade will rest on all 5 three of the fingers. The springs 28 are preferably stiff enough to support the globe without permitting the fingers to rest on the feet of the lugs. This provides a resilient support for the globe and the springs equalize the pressure on the undersurface of the globe.

10 The ring 31 is then revolved to lower it to bring it to the full line position whereupon the edge of the gasket comes against the upper surface of the glass globe opposite the 15 ends 27 of the fingers 25. Sufficient pressure may be applied to compress the springs 28 slightly, thereby insuring that the globe is securely held in place on the globe supporting fingers.

20 The present form of lighting unit is one wherein the globe may be readily inserted or removed and the entrance of dust, water, insects or other foreign matter is effectively prevented by reason of the construction used. 25 There will be no tendency for the globe to loosen or rattle when the unit is subjected to successive vibration such as found on station platforms, and the theft of lamps made more difficult.

30 It is obvious that the invention may be embodied in many forms and constructions within the scope of the claims, and I wish it to be understood that the particular form shown is but one of the many forms. Various modifications and changes being possible, 35 I do not otherwise limit myself in any way with respect thereto.

I claim:

1. A lighting unit comprising a socket support having a plurality of downwardly and outwardly extending lugs, and yieldingly supported fingers carried by the lugs, the fingers extending outwardly to engage under the rim of a shade.

45 2. A lighting unit comprising a socket support having a plurality of downwardly and outwardly extending lugs, yieldingly supported fingers carried by the lugs, the fingers extending outwardly to engage under the rim 50 of a shade, the outside of the socket support being threaded, a threaded cover carried thereby, and a glass shade resting on the spring fingers, with the heel of the shade above the fingers, the cover having a skirt passing down outside the heel of the shade.

55 3. A lighting unit comprising a socket support having a plurality of downwardly and outwardly extending lugs, yieldingly supported fingers carried by the lugs, the fingers 60 extending outwardly to engage under the rim of a shade, the outside of the socket support being threaded, a threaded cover carried thereby, a glass shade resting on the spring fingers, with the heel of the shade above the fingers, the cover having a skirt passing down

outside the heel of the shade, and a gasket carried inside the skirt of the cover for engaging with the upper surface of the glass shade to form a dusttight unit.

4. A lighting suit comprising an externally threaded socket support, a downwardly opening lamp socket therein, downwardly and outwardly extending shade supporting fingers carried by the socket support, and a cover cover ring threaded onto the socket support and having a skirt adapted to be brought down close to the fingers to clamp a shade therebetween, or raised to permit insertion or removal of a shade.

5. A lighting unit comprising an externally threaded socket support, a downwardly opening lamp socket therein, downwardly and outwardly extending shade supporting fingers carried by the socket support, a cover ring threaded onto the socket support and having a skirt adapted to be brought down close to the fingers to clamp a shade therebetween, or raised to permit insertion or removal of a shade, and a detachable canopy carried above the socket support.

6. A lighting unit comprising an externally threaded two part socket support, a downwardly opening lamp socket therein, shade supporting fingers carried by the lower part of the socket support and adapted to extend outwardly underneath a shade, and a clamping ring threaded on the support and adapted to be brought against the upper surface of a shade resting on the fingers, the portions of the support above and below the threads being of larger diameter than the threads and the two part support being separable to permit placing the threaded clamping ring thereon.

7. A dustproof enclosed lighting unit comprising an enclosing globe having an opening at the top, a globe support carrying spring supported fingers engageable underneath the upper surface of the globe for yieldably supporting the globe, and a ring threaded onto the globe support and having a skirt above the upper surface of the globe and opposite the fingers.

8. A dustproof enclosed lighting unit comprising an enclosing globe having an opening at the top, a globe support carrying spring supported fingers engageable underneath the upper surface of the globe for yieldably supporting the globe, a ring threaded onto the globe support, and a gasket carried by the ring and engageable with the upper surface of the globe when the ring is threaded downwardly.

9. A dustproof enclosed lighting unit comprising an enclosing globe having an upper wall provided with an opening, a fixed globe support having fingers engageable under the upper wall of the globe, a ring threaded on the globe support and closing the space between

the globe and the support, and a gasket carried by the ring and passing down outside the heel of the globe to engage the upper surface of the globe.

5 10. In a lighting unit, a ring-like member having downwardly and outwardly extending lugs each provided with slots to receive shade supporting fingers, shade supporting fingers mounted therein and disposed above 10 the lugs, and springs for supporting the fingers.

11. In a lighting unit, a ring-like member having outwardly and downwardly extending lugs carried from the lower edge of the ring, 15 the lugs having outwardly extending feet, fingers overlying the lugs and extending outwardly beyond the feet, the lugs each having a notch to receive the upper portion of a finger and a slot to receive the upper ends 20 thereof, the upper end of the finger being hooked into the slot, and a spring interposed between the foot of the lug and the finger for yieldably supporting the finger above the lug.

12. A lighting unit adapted to be mounted 25 near the ceiling, and comprising a downwardly and inwardly converging canopy detachably fastened to a downwardly extending externally threaded ring carrying downwardly and outwardly extending shade supporting lugs, and a cover ring threaded onto the 30 first ring, the cover ring being confined between the canopy and first ring when these parts are fastened together.

Signed at Meriden, in the county of New 35 Haven and State of Connecticut, this 11th day of April, 1928.
